To all whom it may concern:

Be it known that I, JOHN AUGUST KIESELE, residing in New York city, New York, have invented and produced a new and original Design for a Cake Ornament, of which the following is a specification, reference being had to the accompanying photograph, forming a part thereof, which is a perspective view of my newly-designed cake ornament.

10 A represents the base of my newly-designed cake ornament, which in general appearance represents an inverted basket of fanciful outline. Upon the side of the base A is the representation of a reindeer and chariot, b, driven by a child. Rising from the base A is an arch, c, of flowers and leaves intertwined, and suspended from the center of this arch is a marriage bell, d, of fanciful outline, and having a row of beading at the top and another around 15 the body portion adjacent to the inscription-panel. Beneath the bell d, and standing upon the base A, is the representation of a child, e, representing "Cupid." The child e has a sash around its waist and also a sash passing over 20 its bare shoulders, and carries in its hands a pillow, f, with tassels g g at the corners. Upon 25 the pillow f are rings h h.
